UNITED STATES PATENT OFFICE.

JOHN J. McDONALD, OF ELIZABETHTON, TENNESSEE.

DESIGN FOR A DRESSING CABINET.

Application filed April 10, 1928. Serial No. 26,213. Term of patent 7 years.

To all whom it may concern:

Be it known that I, JOHN J. McDONALD, a citizen of the United States, and a resident of Elizabethhton, in the county of Carter and State of Tennessee, have invented a new, original, and ornamental Design for a Dressing Cabinet, of which the following is a specification, reference being had to the accompanying drawing, forming part thereof.

I claim:

The ornamental design for a dressing cabinet, as shown.

JOHN J. McDONALD.
